UNITED STATES PATENT OFFICE.

MARTEN BALCKER, OF CHICAGO, ILLINOIS, ASSIGNOR TO GEORGE J. GOLDMAN AND NICHOLAS N. GOLDMAN, BOTH OF CHICAGO, ILLINOIS.

PADDING NEEDLE.

Application filed August 19, 1925. Serial No. 51,198.

To all whom it may concern:

Be it known that I, MARTEN BALCKER, a citizen of the United States, residing at Chicago, in the county of Cook and State of Illinois, have invented certain new and useful Improvements in Padding Needles, of which the following is a specification.

This invention relates to improvements in padding needles, particularly adapted, though not necessarily limited in its use for inserting the padding into cushions for automobiles.

The cushions for automobiles are generally formed of pleats or pipes by sewing or fastening two pieces of material together at intervals, and these pleats are then filled with a padding, generally cotton or hair, formed into a bat and threaded into the pipes or pleats.

Heretofore the filling material has usually been inserted by means of tubes of various construction into which the filling bat is threaded before the tube is inserted into the pleats or pipes.

After the tube with the material therein has been inserted into the pipes or pleats, the tube is withdrawn and the filling is allowed to remain in the pipes or pleats.

Heretofore it has been necessary in order to remove the tube without withdrawing the filling material, for the operator to reach over to the other side of the cushion so as to grasp and hold the filling material with one hand, while he withdraws the tube from the other side of the cushion with the other hand. This operation is awkward and inconvenient especially if the cushion is of a considerable width.

Furthermore, with such an operation the material is pulled from the tube with the result that the bat will tear or separate, especially if the bat contains weak spots, which is often the case. The torn or separated material is then wasted or if employed in the cushion, the cushion will not be properly filled.

It is one of the objects of the present invention to overcome these difficulties and objections and to provide an improved padding needle for feeding the material, such as cotton, hair or the like, into the cushion and of such a construction that the operator may use both hands on the same side of the cushion for inserting the filled padding

needle and for withdrawing the needle while the padding is allowed to remain in the pipes or pleats and without necessitating the operator reaching to the other side of the cushion.

A further object of this invention is to provide an improved padding needle of this character from which the pad or bat may be removed by holding upon the pad adjacent the inlet end of the needle so that the pad will, so to speak, be pushed from the needle as distinguished from being pulled from the tube as is necessary with the prior devices, and with the present invention all danger of tearing or separating the bat during the removal of the needle will be avoided.

A further object is to provide an improved form of padding needle which will be automatically opened by the act of withdrawing the needle from the pipes or pleats by reason of the fact that the friction created between the wall of the pipes or pleats upon the members or parts of the needle during the withdrawing operation of the needle will operate to separate the parts or open the needle to reduce the pressure of the parts of the needle upon the bat or filling and thereby allow the bat or filling to be easily ejected or pushed from the needle.

To the attainment of these ends and the accomplishment of other new and useful objects as will appear the invention consists in the features of novelty in substantially the construction, combination and arrangement of the several parts hereinafter more fully described and claimed and as shown in the accompanying drawings illustrating the invention and in which drawings;

Figure 1, is a view partly in top plan, and partly in section showing the needle and the filling or padding inserted in one of the pleats of the cushion and with the latter partly broken away.

Figure 2, is a view similar to Figure 1 showing the needle partially withdrawn.

Figure 3, is a right hand end elevation of Figure 4.

Figure 4, is a sectional view on line 4—4 Figure 6.

Figure 5, is a sectional view on line 5—5 Figure 6.

Figure 6, is a sectional view on line 6—6 Figure 4.

Referring more particularly to the draw-

ings the numeral 10 designates an annular member of any desired configuration but preferably of a somewhat oval shape having a flared extremity 11 to form a mouth to direct the filling material or bat into the annular member.

Connected with the member 10 are supports 13 which form brackets for supporting another annular member 14 which is longitudinally spaced from the member 10 and is arranged in alinement therewith, the diameter of the annular member 14 being larger than the diameter of the member 10.

Connected with the structure thus formed is a handle 15 by means of which the needle may be operated and transported, and if desired the handle may be provided with an aperture 16 for the connection of a flexible suspending device (not shown) to relieve the operator of the weight of the needle and the material.

The needle proper consists of two elongated, opposed and preferably semi-circular members 17 of substantially uniform size and shape one end 18 thereof being shaped to form a pointlike extremity and the other extremity of each member is flared as at 19, and the flared extremities co-operate to assist in directing the filling material or bat between the members 17.

The members 17 are supported preferably by the brackets or supports 13 in such a manner that the members will be adapted for bodily lateral movement towards and from each other and also for bodily longitudinal movement one with relation to the other and also with relation to the supports 13.

The flared ends of the members 17 preferably stand within the supporting structure by passing through the annular member 14 with the flared extremities 19 disposed in proximity to the annular member 10 and in alinement therewith, so that the bat or material passing through the annular member 10 will be directed between the members 17.

The members 17 are supported in any suitable manner to adapt them for the relative lateral and longitudinal movements and to that end links 20 may be provided which are pivotally connected at one end as at 21 preferably to the brackets or supports 13 and are pivotally connected at their other ends as at 22 with the respective members 17 and preferably adjacent the flared ends of the said members.

The links 20 also constitute the means for supporting the members 17 and as the links are swinging about their pivots in one direction the members 17 will be relatively adjusted towards each other to permit the members to grip the bat or filling, and when the links are swung about their pivots in the opposite direction, the members 17 will be separated and thereby release their grip or pressure upon the bat or filling to permit the

latter to be stripped or pushed from the needle and the needle to be withdrawn from the pleat or piping in the cushion.

The annular member 14 serves as a means for limiting the opening or lateral separating movement of the members 17 and the inward movement of these members towards each other may be limited by the flared extremities 19 of the members engaging the edge of the annular member 10.

By reason of the fact that the members 17 are elongated and as the supports therefor are located adjacent the inlet end of the needle, it will be manifest that when the bat or filling is inserted into the needle, the other extremity of the members 17 constituting the point of the needle may be grasped by the hand of the operator and pressed together, in any position of the members 17 with respect to each other, to grip the bat or filling, as well as compress the same to facilitate the insertion of the needle and the filling into the pleats or pipings 23 of the cushion, as the members 17 will then assume positions with respect to each other as to provide a somewhat tapering needle.

In use the bat or material 24 is inserted through the annular member 10 between and for substantially the entire length of the members 17, the latter being preferably, first laterally separated as far as possible.

The operator then grasps with one hand the forward or point end of the needle and compresses the bat by forcing the adjacent portions of the members 17 towards each other. With the other hand the operator opens the end of the pleat or piping 23.

After the end of the needle has been inserted into the end of the pleat the operator may then grasp the handle 15 and force the needle into the pleat until the extremity or point of the needle is adjacent the other end of the pleat or as far into the pleat as it is desired to insert the bat or filling.

It will be noted that the members 17 are arranged and so operate with respect to each other that there will be formed a space between the edges of the members and which space extends from one end to the other end of the needle. This space is important as it enables the operator after the needle with the bat or filling therein is seated in the pipe or pleat, to place one or more fingers of the free hand into the space on the side of the cushion from which he is operating and adjacent the inlet end of the needle, to grip or exert a pressure upon the bat and at the same time withdraw the needle from the pleat. By thus holding the bat, the needle may be removed and the bat will remain in the pleat and during the removing operation of the needle the bat or filling will be stripped or pushed from the needle as distinguished from being pulled therefrom.

As the needle is thus withdrawn from the

pleat the friction created between the outer face of the members 17 and the wall of the pleat or pipe will cause the links 20 to swing about their pivots with the result that 5 a longitudinal movement will be imparted to the members 17 with respect to the support 13 and at the same time the links 20 will cause the members 17 to separate laterally and thereby release the bat or filling 10 from the pressure of the members 17, with the further result that the needle may be easily removed from the pleat and the bat will remain therein.

After the needle has been removed the 15 forward ends of the members 17 may then be gripped and the bat pressed together thereby and while the adjacent edge of the filled pleat is compressed or held by the other hand of the operator, the needle may 20 be manipulated to sever the bat in proximity to the end of the pleat to permit the filling and the needle to be inserted into the next pleat.

With this improved construction all danger 25 of tearing or separating the portion of the bat within the pleat will be avoided and by the use of this improved padding needle the operator may perform his work from one side or edge of the cushion and he will not 30 be required to reach over the cushion to the other side or edge thereof.

While the preferred form of the invention has been herein shown and described, 35 it is to be understood that various changes may be made in the details of construction and in the combination and arrangement of the several parts, within the scope of the claims, without departing from the spirit of this invention.

40 What is claimed as new is,

1. A padding needle for inserting filling into upholstery, said needle embodying opposed elongated members between which the material is held, and means supporting said members for movements laterally one toward and away from the other and for movement longitudinally one with relation to the other, and means for guiding the material between the said members.

50 2. A padding needle for inserting filling into upholstery, said needle embodying opposed elongated members between which the material is held, and means supporting said members for bodily movements laterally one toward and away from the other and for bodily movement longitudinally one with relation to the other, and means for guiding the material between the said members.

60 3. A padding needle for inserting filling into upholstery, said needle embodying opposed elongated members between which the material is held, and means supporting said members for movements laterally one toward and away from the other and for movement longitudinally one with relation to the other.

4. A padding needle for inserting filling into upholstery, said needle embodying opposed elongated members between which the material is held, means supporting said members for movements laterally one with 70 relation to the other and for longitudinal movement one with relation to the other, and an annular member adjacent one end of the first said members for delivering the material between the latter.

5. A padding needle for inserting filling into upholstery, said needle embodying opposed elongated members between which the material is held, means supporting said members for movement laterally one toward 80 and away from the other and for movement longitudinally one with relation to the other, an annular member adjacent one end of the first said members and separate therefrom for delivering the material between the latter, and a handle for supporting the needle.

6. A padding needle for inserting filling into upholstery, said needle embodying opposed elongated and constantly laterally separated members between which the material is held, the material being fed between the members from one end thereof, and means for supporting said members for bodily movements laterally towards and away from each other and for relative longitudinal movement one with relation to the other.

7. A padding needle for inserting filling into upholstery, said needle embodying opposed elongated and constantly laterally separated members between which the material is held, the material being fed between the members from one end thereof, means supporting said members for bodily movements laterally towards and away from each other and for relative longitudinal movements one with relation to the other, and means limiting the lateral separating movements of the said members.

8. A padding needle for inserting filling into upholstery, said needle embodying opposed and elongated disconnected members between which the material is held, said members being mounted with respect to each other to form an unobstructed space therebetween throughout substantially the length of the members whereby an operator may hold the material at the inlet end of the members and withdraw the said members while the material is being held by the operator remote from the other extremity of the needle.

9. A padding needle for inserting filling into upholstery, said needle embodying opposed elongated disconnected members between which the material is held, said members being mounted with respect to each other to form an unobstructed space therebetween throughout substantially the length of the members whereby an operator may

hold the material at the inlet end of the members and withdraw the said members while the material is being held by the operator remote from the other extremity of the needle, the said members being substantially uniform in size and shape.

10. A padding needle for inserting filling into upholstery, said needle embodying opposed and elongated disconnected members between which the material is held, said members being mounted with respect to each other to form an unobstructed space therebetween throughout substantially the length of the members whereby an operator may hold the material at the inlet end of the members and withdraw the said members while the material is being held by the operator remote from the other extremity of the needle, and an annular member independent of and adjacent the inlet end of the said members for delivering the material between the members.

11. A padding needle for inserting filling into upholstery, said needle embodying opposed semi-circular and independent members, laterally spaced to form a continuous space from one end to the other end of the members, and means mounting the members for lateral movements towards and away from each other and for longitudinal movements one with relation to the other.

12. A padding needle for inserting filling into upholstery, said needle embodying opposed semi-circular and independent members laterally spaced to form a continuous space from one end to the other end of the

members, means mounting the members for lateral movements towards and away from each other and for longitudinal movements one with relation to the other, and an annular member independent of and disposed adjacent one end of said members for directing the material therebetween.

13. A padding needle for inserting filling into upholstery, said needle embodying opposed semi-circular and independent members, laterally spaced to form a continuous space from one end to the other end of the members, and means mounting the members for lateral movements towards and away from each other and for longitudinal movements one with relation to the other, in combination with a flexible piping into which the filled needle is adapted to be inserted, the friction created between the piping wall and the said members during the withdrawing operation of the said members serving to laterally separate the said members.

14. A padding needle for inserting filling into upholstery and which contains and grips the material, and means mounting the parts of said needle with respect to each other in a manner that the friction created between the wall of the piping and the said parts of the needle will operate to cause the needle to release the material whereby the material will remain in said piping when the needle is withdrawn from the piping.

In testimony whereof I have signed my name to this specification, on this 13th day of August, A. D. 1925.

MARTEN BALCKER.
